UNITED STATES PATENT OFFICE.

HENRY M. GREEN, OF LOS ANGELES, CALIFORNIA.

PUMP.

1,422,759.

Specification of Letters Patent. Patented July 11, 1922.

Application filed August 31, 1921. Serial No. 497,840.

To all whom it may concern:

Be it known that I, HENRY M. GREEN, a citizen of the United States, residing at Los Angeles, in the county of Los Angeles and State of California, have invented new and useful Improvements in Pumps, of which the following is a specification.

This invention relates to a pump mechanism particularly adapted to be employed for pumping oil wells, and has for its object the provision of a construction including a plunger reciprocating within a working barrel and so arranged that packing is forced, by the weight of liquid above the plunger, outwardly from the latter against the wall of the barrel so as to provide a tight connection at all times. The construction is so arranged that a relatively large supply of this packing may be stored within the plunger and constantly fed downwardly and outwardly against the wall of the pump barrel as it is worn away, so that the pump may be operated for a long time without renewing the packing.

It is a further object of the invention to so arrange the pump that, at all sliding contacts between parts thereof, a cup construction is provided upon the inner member of said sliding contacting member so that any sand or dirt falling through the pump structure will be collected in said cup arrangement and directed into the flowing oil or other fluid for withdrawal from the well, instead of making its way downwardly between the sliding contacting parts and thereby causing friction and wear.

It is a still further object of the invention to provide a pump structure wherein a plunger is slidably mounted within a barrel with its lower end received over a standing valve positioned in the barrel, and so arranged that when the plunger structure is withdrawn from the pump barrel the standing valve structure will also be withdrawn. A construction is thus provided whereby the pump barrel received within a wall may be cleared by a single pulling operation upon the end of the plunger structure.

The invention will be readily understood from the following description of the accompanying drawings, in which—

Figure 1 is a longitudinal section through an outer casing received within a well and having the improved pump mechanism mounted therein and shown partly in side elevation and partly in longitudinal section.

Figs. 2, 3 and 4 are detail longitudinal sections on the lines 2—2, 3—3 and 4—4 of Fig. 1.

Fig. 5 is a transverse section on the line 5—5 of Fig. 3.

Fig. 6 is a transverse section on the line 6—6 of Fig. 4.

The working barrel of the pump is shown at 1, and contains the pumping mechanism consisting essentially of a plunger working in casing 1, and having inner and outer spaced sleeves, of which the inner sleeve is connected at its lower end to a plunger nut, and having the outer sleeve continued above the inner sleeve and terminating in a usual rod fitting to which is attached the operating rod for reciprocating the plunger. A standing valve is mounted in the working barrel below the plunger so as to extend upwardly within the same, and this standing valve is so arranged that when the plunger is withdrawn from the barrel, it will be engaged by the plunger so as to be withdrawn with the same.

80
A supply of packing is stored between the inner and outer sleeves of the plunger adjacent its lower end, and the outer sleeve of the plunger is spaced from the plunger nut so that this packing is forced outwardly to form a tight joint between the plunger and the working barrel. A sleeve rests upon this packing and extends upwardly between the inner and outer sleeves of the plunger with a cross bar resting upon the upper end 90 of this sleeve and extending through longitudinal slots in the inner sleeve of the plunger, so that the bar and the sleeve upon which it rests may be forced downwardly with relation to the plunger so as to force 95 the packing outwardly against the wall of the pump barrel.

95
A tubing is mounted upon the cross bar within the plunger and extends upwardly with a sliding contact provided between the upper end of this tube and the plunger and a valve arranged to close the upper end of the tube. The sliding contact between the tube and plunger includes a suitable stuffing box for preventing return of the oil raised 105 by the plunger past the valve between the tube and the plunger wall.

At the various points where sliding contacts are provided between parts of the pump structure as thus described, downwardly converging cup members are provided upon the upper ends of the inner mem-

bers of the parts forming the sliding contacts, so that any sand or dirt falling through the structure will be directed by said cup arrangements from said sliding contacts to the central bore of the pump mechanism and into the line of the flowing liquid.

Referring specifically to the construction as thus set forth, the plunger is shown as comprising a rod fitting 2 received within 10 pump barrel 1 and secured to a tube connection 3 having liquid outlet ports 4 whereby the liquid pumped through the plunger structure is discharged to the pump barrel and from thence into the pump tubing connected to said barrel, for raising said liquid. Tube 3 is connected at its lower end to an upper plunger nut 5, and a cup 6 is received around tube 3 above said plunger nut and is so arranged as to collect therein any 20 falling sand or dirt and direct the same away from the sliding contact between said cup and plunger and the pump barrel.

The upper plunger nut is connected to the outer sleeve 7 of the plunger which extends 25 downwardly within pump barrel 1 and is arranged for sliding contact therewith. This outer sleeve of the plunger is an upper section of said sleeve and is connected at its lower end by a coupling 8 to the lower section 9 of the outer plunger sleeve. An inner plunger sleeve 10 is also connected to coupling 8 so as to extend downwardly in spaced 30 relation within sleeve section 9. The inner sleeve 10 is provided with longitudinal slots 35 11, and a cross bar 12 is mounted in the inner sleeve with its ends received in said slots for reciprocation therein.

A tubing 14 rests upon cross bar 12 and extends upwardly within the upper section 40 of the outer plunger sleeve. This tube terminates a short distance below upper plunger nut 5 in a valve seat 15 arranged at the base of a cup structure 15 similar to that previously described, so as to direct falling sand 45 away from the sliding contact between said valve seat and the plunger sleeve 7 and toward the axial bore through said valve seat. A ball valve 16 forming an upwardly opening check valve is received upon the valve 50 seat for closing the axial opening provided through the pump structure. Upward movement of the ball valve is limited by a cross bar 17 carried by cup 15.

The member 15 also forms the upper part 55 of a stuffing box provided between tube 14 and the sleeve 7 of the plunger. For this purpose suitable packing 18 is received against the lower surface of member 15, and a suitable lower part 19 of the stuffing box is 60 secured to tube 14 so as to be received against the lower surface of the packing.

A sleeve 20 is received between the inner and outer sleeves 9 and 10 of the plunger below cross rod 12. At its lower end a ring 21 65 is fixed to this sleeve for sliding movement

within the space between the sleeves of the plunger and adapted to impinge against packing 22 stored between the sleeves of the plunger. This packing is, preferably, a sleeve structure and extends downwardly 70 from ring 21 to a point adjacent the lower end of the plunger. The plunger nut 23 is mounted upon the lower end of inner sleeve 10 of the plunger and extends outwardly toward outer casing 1 with the outer sleeve 9 75 of the plunger terminating short of said plunger nut so as to provide a space 24 leading from the space between the sleeves of the plunger to the pump barrel 1.

Packing 22 extends outwardly through 80 this space and against the wall of pump barrel 1 so as to provide a tight connection between the sliding plunger and the pump barrel. As this packing is worn away the store of packing within the space between the 85 plunger sleeves is forced downwardly so as to maintain at all times a tight connection between the plunger and the pump barrel. It will be noted that the packing will be forced downwardly by sleeve 20 which is in 90 turn forced downwardly by cross bar 12 having tube 14 resting upon the same. This tube is forced downwardly by the weight of the liquid above valve 16 resting upon the same.

A standing valve is arranged in the pump barrel 1 below the lower end of the plunger so as to extend upwardly within the axial bore of the plunger. For this purpose a tapering seat 25 is provided in pump barrel 1 100 below the plunger, and a seat 26 of the standing valve, similarly tapered, rests upon the seat 25. A bushing 27 depends from seat 26, and a valve seat 28 is formed within seat 26 for a ball valve 29 forming an upwardly opening check valve. A tube 30 of the standing valve extends upwardly from seat 26 and is secured thereto by the connection 31, said tube being received within the bore of the plunger.

At the upper end of tube 30 a cup member 33, similar to those previously described, is mounted upon the tube so as to provide a construction for directing falling sand away from the sliding contact provided between 115 said cup and the inner sleeve of the plunger. A ball valve 34 is received upon a valve seat arranged at the base of the cup so as to provide an upwardly opening check valve, and the upward movement of this ball valve 120 is limited by a cross bar 35 carried by cup 33.

Cup member 33 forms an annular shoulder 36 extending beyond tube 30, and the lower plunger nut 23 forms an annular shoulder 37 extending inwardly from plunger sleeve 10 125 and in alignment with shoulder 36, so that when the plunger is raised a distance greater than its normal limit of reciprocation for providing the pumping action, shoulder 37 will impinge against shoulder 36, and by 130

pulling the plunger from pump barrel 1 the standing valve of the pump may be thus pulled from the pump barrel with the plunger.

5 In operation the plunger is reciprocated in usual manner so as to draw liquid past check valve 29 in usual manner and into the tube of the standing valve from whence it is drawn past check valve 34 into the bore of 10 the plunger. The liquid within the plunger is then forced past check valve 16 and outwardly through port 4 into the pump barrel and thence into the pump tubing, so as to be raised therein by the continued reciprocation 15 of the plunger. As previously stated, the weight of the oil upon check valve 16 will cause sleeve 20 to be forced downwardly upon packing 22 and thereby force the latter outwardly as it is worn, for maintaining 20 a tight joint between the plunger and the pump barrel. It will also be noted that the provision of cups 6, 15 and 33 arranged at the respective points of sliding contact between parts of the pump, will direct falling 25 sand and dirt inwardly to the axial bore of the pump so that the same will be withdrawn from the well by the ascending column of liquid, instead of passing downwardly between the contacting surfaces. By this arrangement friction and undue wear between 30 the parts forming the sliding contacts are eliminated.

It will be understood that the upper edges of the cups, as thus arranged, may be made 35 as sharp as found expedient, in order to thus direct all of the falling sand away from the sliding contacts formed by the pump structure.

Various changes may be made without departing from the spirit of the invention as 40 claimed.

What is claimed is:

1. A pump including a working barrel and having a reciprocating plunger, and 45 packing within and adapted to be forced from one end of said plunger against said barrel by the weight of the pumped fluid above said plunger.

2. A pump including a working barrel 50 and having a reciprocating plunger, packing within said plunger and adapted to be forced therefrom against said working barrel, a member slidably received within said plunger and resting upon said packing to force 55 the same outwardly by the weight of the pumped fluid upon said member, and packing provided between said member and the plunger.

3. A pump including a working barrel 60 and having a reciprocating plunger, packing within said plunger and adapted to be forced therefrom against said working barrel, a member slidably received within said plunger and resting upon said packing to force 65 the same outwardly by the weight of the

pumped fluid upon said member, and a check valve within the bore of said member.

4. In a pump for wells, a working barrel, a plunger within the barrel, a packing within the plunger and having a projecting portion, 70 a member associated with the plunger to cause said projecting portion to engage the wall of said barrel, and means responsive to the weight of the pumped fluid above the plunger for constantly forcing the packing 75 from the plunger so that as the projecting portion wears away a new portion will be substituted.

5. A pump including a working barrel, a reciprocating plunger within the barrel, a packing within the plunger adapted to be forced therefrom against the working barrel, and a member slidably within the plunger and resting upon the packing to force the latter outwardly from the plunger by the 80 weight of the pumped fluid upon said member.

6. A pump including a working barrel, a reciprocating plunger within the barrel, a valve member within the plunger operating 90 to support the fluid in the barrel and above the plunger during the limiting stroke of the plunger, a packing within the plunger and adapted to be ejected therefrom against the working barrel, and means between the 95 valve member and packing which operates to respond to the weight of the fluid on said member to force the packing from said plunger.

7. A pump including a working barrel, a 100 plunger slidable within the working barrel, a valve member slidable within the plunger, and a packing mounted within the plunger to be engaged by said member and forced therefrom against the working barrel by the 105 weight of the pumped fluid acting on said member.

8. In a pump, a working barrel, a plunger within the working barrel having a lower portion comprising sleeves spaced apart to 110 provide a storage space, a packing stored within said space and having a portion thereof projecting from the lower ends of the sleeves to engage said working barrel, and means engaging the upper end of the 115 packing for constantly exerting a downward force on the packing to maintain the projecting end thereof in contact with the barrel.

9. In a pump, a working barrel, a plunger 120 within the barrel and comprising an upper sleeve, spaced lower sleeves, a valve member slidable in the upper sleeve, a packing between the lower sleeves having a portion thereof in contact with said barrel, and 125 means within the plunger responsive to the movement of said valve member for exerting pressure on said packing to maintain the latter as it wears in contact with said barrel.

10. In a pump for wells, a plunger having 130

- a packing receiving chamber, a packing sleeve within the chamber with one end projecting therefrom, a valve member movable within the plunger, and means between the member and packing sleeve for feeding the latter from the chamber when the valve member is moved in one direction.
11. In a pump for wells, a working barrel, a plunger within the working barrel having a packing receiving chamber, a packing sleeve within the chamber having one end projecting therefrom, a packing directing member associated with the chamber for causing the projecting portion of the packing sleeve to engage said barrel, a valve member movable within the plunger, and means between the valve member and packing sleeve for urging the latter outwardly of the chamber.
12. In a pump for wells, a working barrel, a plunger within the barrel, a packing within the plunger and having a projecting end engaging the barrel, and means responsive to the weight of the pumped fluid above the plunger for constantly forcing the packing from the plunger so that as the projecting end wears away a new portion will be substituted.
- In testimony whereof I have signed my name to this specification.

H. M. GREEN
